(57) **CLAIM**

The ornamental design for a mascara brush, as shown and described.

DESCRIPTION

FIG. 1 is a perspective view of the mascara brush;
FIG. 2 is a front elevational view of the mascara brush shown in FIG. 1;

FIG. 3 is a rear elevational view of the mascara brush shown in FIG. 1;

FIG. 4 is a left-side elevational view of the mascara brush shown in FIG. 1;

FIG. 5 is a right-side elevational view of the mascara brush shown in FIG. 1;

FIG. 6 is a top plan view of the mascara brush shown in FIG. 1; and

FIG. 7 is a bottom plan view of the mascara brush shown in FIG. 1.

FIG. 8 is a perspective view of a second embodiment of the mascara brush;

FIG. 9 is a front elevational view of the mascara brush shown in FIG. 8;

FIG. 10 is a rear elevational view of the mascara brush shown in FIG. 8;

FIG. 11 is a left-side elevational view of the mascara brush shown in FIG. 8;

FIG. 12 is a right-side elevational view of the mascara brush shown in FIG. 8;

FIG. 13 is a top plan view of the mascara brush shown in FIG. 8; and,

FIG. 14 is a bottom plan view of the mascara brush shown in FIG. 8.

The broken lines illustrate portions of the article that form no part of the claimed design.

The color and surface features of the mascara brush form no part of the claimed design.

1 Claim, 14 Drawing Sheets
